DESIGN FOR A CAKE CHEST OR SIMILAR ARTICLE

Maxine S. Dumke, near Fontana, Calif.

Application November 17, 1947, Serial No. 142,572

Term of patent 7 years

(Cl. D44—5)

To all whom it may concern:

Be it known that I, Maxine S. Dumke, a citizen of the United States, residing near Fontana, in the county of San Bernardino and State of California, have invented a new, original, and ornamental Design for a Cake Chest or Similar Article, of which the following is a specification, reference being had to the accompanying drawing, forming a part thereof.

I claim:

The ornamental design for a cake chest or similar article, substantially as shown.

MAXINE S. DUMKE.
